UNITED STATES PATENT OFFICE.

JAMES S. THOMPSON, OF PELHAM, NEW YORK.

BRAKE SHOE MOLD.

Application filed July 20, 1923. Serial No. 652,769.

To all whom it may concern:

Be it known that I, JAMES S. THOMPSON, a citizen of the United States, residing at Pelham, in the county of Westchester and State of New York, have invented certain new and useful Improvements in Brake Shoe Molds, of which the following is a specification.

This invention relates to the manufacture of brake shoes and more particularly to the mold in which the shoe is cast, and its object is broadly to enable a brake shoe of approved type with an integral composite wearing face to be cast in a permanent mold 15 as well as it can be cast in a sand mold and with the additional advantages of reduction in time and cost.

To explain my invention more readily reference may be had to an approved type 20 of car shoe which is standard on a great many railroads at the present time and which has a cast iron body reinforced at the back with a skeleton steel plate embedded therein and having chilled end portions to provide a composite wearing face 25 designed to give long life and requisite friction. The method now employed of making these shoes in green sand molds with chill blocks suitably disposed to produce the chilled ends has been common foundry practice for many years, it is a comparative- 30 ly slow operation, it involves much hard and disagreeable work and the labor cost is considerable. Efforts have been made in 35 the past to cast brake shoes in permanent molds providing metal contact with the casting but, so far as I know, and I have been engaged in the manufacture of brake shoes for many years, none of these efforts has been commercially successful, notwithstanding the fact that metal molds have 40 been used in making many castings and considerable development in the general branch of the art of casting in permanent molds 45 has been made.

The reason that brake shoes have not been successfully made commercially in permanent molds is because of the comparatively large volume of solid metal, the necessity for producing a wearing face of a predetermined composite character, and other difficulties which are or will be readily apparent to foundrymen and manufacturers of brake shoes. It may be stated, briefly, 50 that the metal molds affect the surface of the shoe, producing a change in the texture

of the body of the shoe, which varies in depth, and generally prevents the production of a shoe having the desired strength and friction qualities essential for its service. I am quite sure that the modern standard car shoe of the type above mentioned and having an integral composite wearing face has never before been cast with commercial success in a metal mold.

This modern standard type of car shoe with an integral composite wearing face having chilled end portions and an intermediate unchilled soft iron portion or portions has been developed as the 70 result of a long period of investigation and tests and commercial use of a great many different types of shoes, and the work has been carried on not only by manufacturers of brake shoes and their engineers but by 75 and on behalf of the railroads and their engineers, and the problem has been to produce a shoe at a fair cost having the requisite life, strength and friction qualities essential for its service under modern conditions of railroad service. This shoe, which I have referred to as an approved type standard on many railroads, is the result of the combined effort of all those who have been working in the art and is today 80 meeting all requirements with substantial satisfaction.

The object of my invention is to enable 85 said approved standard type of brake shoe with a steel back and chilled end portions and intermediate soft iron portion or portions, as well as other types of shoes, to be cast satisfactorily on a commercial scale in a permanent mold, to have all of the desirable qualities of similar shoes made in sand 90 molds and capable of being used interchangeably with sand mold shoes.

In the accompanying drawings illustrating 95 selected embodiments of my invention

Fig. 1 is a longitudinal sectional view 100 showing a metal mold adapted for making a brake shoe having a steel back and chilled end portions;

Fig. 2 is a transverse sectional view on the line 2—2 of Fig. 1;

Fig. 3 is a longitudinal sectional view 105 similar to Fig. 1 but showing the use of refractory coatings instead of refractory sections;

Fig. 4 is a transverse sectional view on the line 4—4 of Fig. 3.

Referring to the drawings, 5 represents the

drag and 6 the cope of a metal mold having a pouring gate 7 preferably located at one end. A brake shoe 8 is shown in the mold cavity which is formed principally in the drag by a channel recess having an end wall 9, a bottom wall 10 and side walls 11, 11, for the end, wearing face and sides of the shoe. The cope is shaped complementary to the drag and has a wall 12 forming the top wall of the mold cavity, and an end wall 13 forming the other end wall of the mold cavity. This mold cavity thus formed in the drag and cope will be shaped, of course, to produce the type of shoe desired and to this end it may be changed as required.

It is desirable that a substantial portion of the body of the shoe should be unaffected by the metal mold in order to provide a shoe having the required life, strength and friction qualities; and to this end I provide the walls of the mold cavity with refractory sections located so as to protect the adjacent portions of the shoe from chilling action by the metal mold, the other parts of the walls being left bare so that the cast metal of the shoe may be chilled by the metal mold at these parts whereby an integral composite shoe may be uniformly produced in metal molds as desired.

Referring to Figs. 1 and 2, a refractory section 14 is seated in the wall 10 of the mold cavity and is preferably made with a bottom and sides to form a channel cavity for the body of the shoe intermediate of its end portions. This refractory section may be of greater or less length and it may be made discontinuous but I prefer to provide a continuous channel section extending from one end portion to the other end portion of the mold cavity as shown at 14 in the drawings. The end walls 9 and 13 and the adjacent portion of the bottom wall 10 and side walls 11 of the mold cavity are left bare so that the metal mold will have its chilling effect upon the end portions of the shoe to chill the same as indicated. These chilled portions are beyond the ends of the soft unchilled portion of the shoe which has been protected from chilling by the refractory section 14. Refractory sections 15 are provided in the cope at the upper corners of the mold cavity to protect the end stops 16 and the adjacent portions of the shoe from chilling.

I provide an opening 17 of substantial size in the cope to receive a sand plug 18 which is preferably made in a holder or container 19 which fits snugly in the opening 17, and has a recess 18' forming part of the mold cavity. I provide the plug with one or more wires 22 supported from a cross-bar 23 at the top of the plug and having their free ends projecting through the inner end of the plug. After the plug is inserted in the opening 17 the steel lug 20 and the baked sand core 21 are placed in the plug as shown and

the reinforcing back 24 is seated against the mold cavity wall 12 in the cope. The wire ends are engaged with the reinforcing back 24 and are twisted together to hold the lug 20, core 21 and back 24 securely and rigidly in place during the molding operation. The reinforcing back, which has been found very satisfactory for brake shoes of this type, is recessed at its sides and midway between its ends, as indicated at 25, and the wires 22 are preferably located on opposite sides of the lug 20 to be engaged with this recessed portion of the back. While this may be considered a detail of the invention it is, in fact, an important feature because of the necessity for holding the back in its proper position in the mold cavity while the mold is being closed and during the pouring operation. I have shown a flat cross-bar 23 of sufficient width to space the wires so that they will pass through the plug on opposite sides of the lug 20 to engage the recesses 25 at the sides of the back, which is a desirable arrangement for the particular type of shoe illustrated, but other arrangements may be made within the scope of my invention as will be found desirable for other types of shoes and backs. The cross-bar 23 and the wires 22 may be arranged in position with respect to the holder before the plug 18 is formed therein, in which case the cross-bar may be made fast to the holder, or the cross-bar and the wires may be applied after the plug has been formed.

Instead of employing the refractory sections 14, 15, as shown in Figs. 1 and 2, I may provide the walls of the mold cavity with a coating of refractory material in sections 14' and 15' corresponding, to all intents and purposes, with the sections 14 and 15, and the sections 15' may be extended as indicated by 15" to the opening 17', if desired. The sections 15 of Fig. 1 may be likewise extended if found desirable.

My invention overcomes the difficulties which have been experienced heretofore in the manufacture of brake shoes in metal molds and particularly in the manufacture of shoes having an integral composite wearing face which, as hereinbefore stated, are a type of shoe found to be especially desirable as regards life, strength and friction qualities and are extensively used and standard on many railroads. By my invention a shoe of this type can be cast in metal molds with the texture and other characteristics similar to a corresponding shoe cast in an ordinary sand mold and, of course, it can be cast in much less time and with a corresponding reduction in cost. The invention insures a uniformity of the product which is highly essential in brake shoes in order that they may properly respond to all the requirements and give the requisite friction when the brakes are applied ac-

cording to conditions of speed and pressure so that engineers may be assured of the results which they expect. The means employed for holding the lug, the baked sand core and the reinforcing back in place are important in order that the shoes may be uniform and waste avoided. The sand plug permits the escape of gases therethrough during the casting operation and insures the production of shoes of uniform size, shape and texture free from deformations and blow-holes. When the casting operation is completed and the mold is opened the shoe can be readily removed therefrom. The wires are to a more or less extent oxidized during the casting operation so that the shoe will be easily released but if they are not sufficiently oxidized to permit the release of the shoe the cross-bar can be withdrawn and the wires pulled through the plug and afterwards broken off.

I am aware that changes in the form and construction and arrangements of parts may be made to adapt my invention to different sizes, shapes and types of shoes, lugs and backs, and I consider myself entitled to make all such changes as fairly fall within the scope of the invention.

I claim:

1. A mold for casting a brake shoe having an integral composite body, and comprising a metal drag and a metal cope with a brake shoe mold cavity therein, parts of the walls of said cavity being bare metal of said drag and cope and intermediate parts of the walls of said cavity being composed of solid refractory material so that those portions of the shoe casting opposite the bare metal parts of the cavity walls will be chilled and those portions of the shoe casting opposite the refractory parts of the cavity walls will be free from chilling effect of the metal drag and cope to produce an integral shoe body casting composed in part of soft cast iron and in part of chilled iron.

2. A mold for casting a brake shoe having an integral composite body, and comprising a metal drag and a metal cope with a brake shoe mold cavity formed in said drag and cope, the surface of the cavity walls in the drag and cope being composed of separate areas of bare metal constituting integral parts of the drag and cope and refractory material.

3. A mold for casting a brake shoe having an integral composite body, and comprising a metal drag and a metal cope with a brake shoe mold cavity formed in part in the drag and in part in the cope, the surface of the walls at the ends of the mold cavity being bare metal constituting integral parts of the drag and cope and the surface of the walls of the mold cavity between said bare ends being composed of refractory material to produce a shoe casting with

chilled ends and soft iron intermediate portions.

4. A mold for casting a brake shoe having an integral composite body, and comprising a metal drag and a metal cope with a brake shoe mold cavity therein, the bottom wall and one end wall of the mold cavity being formed in the drag, and the top wall and the other end wall of the mold cavity being formed in the cope, portions of said walls being bare and other portions having a refractory facing to produce an integral shoe body casting composed in part of chilled iron and in part of soft cast iron.

5. A mold for casting a brake shoe having an integral composite body, and comprising a metal drag and a metal cope with a brake shoe mold cavity therein, the bottom, sides and one end wall of said cavity being formed in the drag, and the top and other end wall of said cavity being formed in the cope, the end walls in the drag and cope and adjacent portions of the bottom and side walls in the drag being bare to chill the casting, and other portions of the cavity walls having a refractory facing to prevent chilling the oppositely disposed portions of the shoe casting.

6. A mold for casting a brake shoe having an integral composite body, and comprising a metal drag and a metal cope with a brake shoe mold cavity therein, sections of refractory material set into the walls of the mold cavity to form a refractory surface in the bottom and side walls of the cavity intermediate of its ends and in the top wall of the cavity at its ends to prevent the metal of the drag and cope from chilling the shoe casting opposite said refractory surfaces while the bare metal of the drag and cope intermediate of said refractory surfaces is permitted to chill the shoe casting to produce an integral shoe body casting composed in part of soft cast iron and in part of chilled iron.

7. A mold for casting a brake shoe, and comprising a metal drag and a metal cope having a mold cavity therein, said cope having an opening communicating with the mold cavity, a soft sand plug seated in said opening, and supporting means carried by said plug and projecting into said mold cavity and adapted to be engaged with a reinforcing back to be embedded in the shoe casting to support said back in the mold cavity during the casting operation.

8. A mold for casting a brake shoe, and comprising a metal drag and a metal cope having a mold cavity therein, said cope having an opening communicating with the mold cavity, a soft sand plug seated in said opening, a reinforcing back having recessed sides adapted to be embedded in the shoe casting, and supporting means carried by

1. A mold for casting a brake shoe, and comprising a metal drag and a metal cope having a mold cavity therein, said cope having an opening extending therethrough and communicating with the mold cavity, a sand plug seated in said opening, a recess forming a part of the mold cavity, and means for supporting the attaching lug and the core for forming the opening in said lug in said recess.
2. A mold for casting a brake shoe, and comprising a metal drag and a metal cope having a mold cavity therein, said cope having an opening communicating with the mold cavity, a soft sand plug seated in said opening, a reinforcing back adapted to be embedded in the shoe casting, and supporting means in said plug projecting into said cavity and adapted to be engaged with said back to support the back in the cavity during the casting operation, said supporting means comprising a looped wire having its legs extending through the plug in substantially parallel relation, and a transverse supporting bar engaged with the loop and spacing the legs apart.
3. A mold for casting a brake shoe, and comprising a metal drag and a metal cope having a mold cavity therein, said cope having an opening communicating with the mold cavity, a removable holder adapted to fit in said opening, a soft sand plug carried by said holder, a cross bar engaging the top of the holder, and a looped wire engaged with said cross bar and projecting through the plug into the cavity to support a metal back adapted to be embedded in the shoe during the casting operation.
4. A mold for casting a brake shoe, and comprising a metal drag and a metal cope having a mold cavity therein, said cope having an opening of substantial size extending therethrough and communicating with the mold cavity, a sand plug seated in said opening and having a recess adapted to receive the attaching lug and the core for forming the opening in said lug, and means for securing the lug and core in the recess in said plug.
5. A mold for casting a brake shoe, and comprising a metal drag and a metal cope having a mold cavity therein, said cope having an opening of substantial size extending therethrough and communicating with the mold cavity, a sand plug seated in said opening and provided with a recess forming a part of the mold cavity and adapted to receive the attaching lug and the core for forming the opening therein, and means extending through the plug for securing said lug and core in place.
6. A mold for casting a brake shoe, and comprising a metal drag and a metal cope having a mold cavity therein, said cope having an opening larger than the attaching lug and the core for forming the opening therein and communicating with the mold cavity, a sand plug seated in said opening and having a recess adapted to receive the lug and the core therefor, and means for securing the lug and core in said recess.
7. A mold for casting a brake shoe, and comprising a metal drag and a metal cope having a mold cavity therein, said cope having an opening extending therethrough and communicating with the mold cavity, a sand plug seated in said opening, and provided with a recess forming a part of the mold cavity, and means for supporting the attaching lug and the core for forming the opening in said recess.
8. A mold for casting a brake shoe, and comprising a metal drag and a metal cope having a mold cavity therein, said cope having an opening extending therethrough and communicating with the mold cavity, a sand plug seated in said opening, and means embedded in the plug and projecting into the mold cavity for securing in place in the cavity the parts to be embedded in the shoe casting.
9. A mold for casting a brake shoe, and comprising a metal drag and a metal cope having a mold cavity therein, said cope having an opening extending therethrough and communicating with the mold cavity, a sand plug seated in said opening, and wires carried by the plug and projecting into the mold cavity for securing in place in the cavity the parts to be embedded in the shoe casting.
10. A mold for casting a brake shoe, and comprising a metal drag and a metal cope having a mold cavity therein, said cope having an opening extending therethrough and communicating with the mold cavity, a sand plug seated in said opening, and forming a part of the top wall of the mold cavity, and means carried by the plug and projecting into the mold cavity for securing in place in the cavity the parts to be embedded in the shoe casting.
11. A mold for casting a brake shoe, and comprising a metal drag and a metal cope having a mold cavity therein, said cope having an opening extending therethrough and communicating with the mold cavity, a sand plug seated in said opening, and provided with a recess forming a part of the mold cavity and adapted to receive the attaching lug and the core for forming the opening therein, and means extending through the plug for securing said lug and core in place.
12. A mold for casting a brake shoe, and comprising a metal drag and a metal cope having a mold cavity therein, said cope having an opening extending therethrough and communicating with the mold cavity, a sand plug seated in said opening, and provided with a recess forming a part of the mold cavity and adapted to receive the attaching lug and the core for forming the opening therein, and means extending through the plug for securing said lug and core in place.
13. A mold for casting a brake shoe, and comprising a metal drag and a metal cope having a mold cavity therein, said cope having an opening larger than the attaching lug and the core for forming the opening therein and communicating with the mold cavity, a sand plug seated in said opening and having a recess adapted to receive the lug and the core therefor, and means for securing the lug and core in said recess.
14. A mold for casting a brake shoe, and comprising a metal drag and a metal cope having a mold cavity therein, said cope having an opening extending therethrough and communicating with the mold cavity, a sand plug seated in said opening, and provided with a recess forming a part of the mold cavity, and means for supporting the attaching lug and the core for forming the opening in said recess.
15. A mold for casting a brake shoe, and comprising a metal drag and a metal cope having a mold cavity therein, said cope having an opening extending therethrough and communicating with the mold cavity, a sand plug seated in said opening, and means embedded in the plug and projecting into the mold cavity for securing in place in the cavity the parts to be embedded in the shoe casting.
16. A mold for casting a brake shoe, and comprising a metal drag and a metal cope having a mold cavity therein, said cope having an opening extending therethrough and communicating with the mold cavity, a sand plug seated in said opening, and wires carried by the plug and projecting into the mold cavity for securing in place in the cavity the parts to be embedded in the shoe casting.
17. A mold for casting a brake shoe, and comprising a metal drag and a metal cope having a mold cavity therein, said cope having an opening extending therethrough and communicating with the mold cavity, a sand plug seated in said opening, and forming a part of the top wall of the mold cavity, and means carried by the plug and projecting into the mold cavity for securing in place in the cavity the parts to be embedded in the shoe casting.
18. A mold for casting a brake shoe having an integral composite body, and comprising a metal drag and a metal cope having a brake shoe mold cavity therein, parts of the walls of said cavity being bare metal of said drag and cope and intermediate parts of the walls of said cavity being composed of refractory material, so that those portions of the shoe casting opposite the bare metal parts of the cavity walls will be chilled and those portions of the shoe casting opposite the refractory parts of the cavity walls will be free from chilling effect of the metal drag and cope to produce an integral shoe body casting composed in part of soft cast iron and in part of chilled iron, said cope having an opening communicating with the mold cavity, and a plug in said opening forming a vent for the mold.
19. A mold for casting a brake shoe having an integral composite body, and comprising a metal drag and a metal cope with a brake shoe mold cavity therein, parts of the walls of said cavity being

- bare metal of said drag and cope and intermediate parts of the walls of said cavity being recessed, solid refractory sections fitting snugly in said recesses and
- 8 abutting against the walls thereof to provide continuous unbroken walls for the mold cavity, whereby those portions of the shoe casting opposite the bare metal parts of the cavity walls will be chilled and those
- 10 portions of the shoe casting opposite the refractory parts of the cavity walls will be free from chilling effect of the drag and cope to produce an integral shoe body casting composed in part of soft cast iron
- 15 and in part of chilled iron.
20. A mold for casting a brake shoe having an integral composite body, and comprising a metal drag and a metal cope with a brake shoe mold cavity therein,
- 20 parts of the walls of said cavity being bare metal of said drag and cope and intermediate parts of the walls of said cavity being recessed, solid refractory sections fitting snugly in said recesses and
- 25 abutting against the walls thereof to provide continuous unbroken walls for the mold cavity, whereby those portions of the shoe casting opposite the bare metal parts of the cavity walls will be chilled and those
- 30 portions of the shoe casting opposite the refractory parts of the cavity walls will be free from chilling effect of the drag and cope to produce an integral shoe body casting composed in part of soft cast iron
- 35 and in part of chilled iron, said cope having an opening communicating with the mold cavity, and a plug seated in said opening and forming a vent for the mold.
21. A mold for casting a brake shoe having an integral composite body, and comprising a metal drag and a metal cope with a brake shoe mold cavity therein,
- 40 parts of the walls of said cavity being bare metal of said drag and cope and intermediate parts of the walls of said cavity being recessed, solid refractory sections fitting snugly in said recesses and
- 45 abutting against the walls thereof to provide continuous unbroken walls for the mold cavity, whereby those portions of the shoe casting opposite the bare metal parts of the cavity walls will be chilled and those
- 50 portions of the shoe casting opposite the refractory parts of the cavity walls will be free from chilling effect of the drag and cope to produce an integral shoe body casting composed in part of soft cast iron
- 55 and in part of chilled iron, said cope having an opening communicating with the mold cavity, a plug seated in said opening and forming a vent for the mold, a reinforcing back adapted to be embedded in the shoe casting, and supporting means in said plug projecting into said cavity and adapted to be engaged with said back to support the back in the cavity during the
- 60 casting operation.

JAMES S. THOMPSON.
